US00D598844S

(12) United States Design Patent
Harrison et al.

(10) Patent No.: US D598,844 S
(45) Date of Patent:  Aug. 25, 2009

(54) RECHARGEABLE BATTERY

(75) Inventors: Ryan Harrison, Anderson, SC (US);
Taku Ohi, Greer, SC (US)

(73) Assignee: Techtronic Power Tools Technology Limited, Tortola (VG)

() Term: 14 Years

(21) Appl. No.: 29/330,417

(22) Filed: Jan. 7, 2009

(51) LOC (9) Cl. 13-02

(52) U.S. Cl. D13/103

(58) Field of Classification Search D13/102-108,
D13/110, 118-119, 184; 429/96-100, 163,
429/176

(57) CLAIM

We claim the ornamental design for a rechargeable battery, as shown and described.

DESCRIPTION

FIG. 1 is a perspective view of a rechargeable battery of the present invention.

FIG. 2 is a front-side view of the rechargeable battery of FIG. 1.

FIG. 3 is a rear-side view of the rechargeable battery of FIG. 1.

FIG. 4 is a right-side view of the rechargeable battery of FIG. 1.

FIG. 5 is a left-side view of the rechargeable battery of FIG. 1.

FIG. 6 is a top view of the rechargeable battery of FIG. 1; and, FIG. 7 is a bottom view of the rechargeable battery of FIG. 1.

1 Claim, 4 Drawing Sheets

FIG. 1

FIG. 2FIG. 3

FIG. 5

FIG. 6

FIG. 7
